UNITED STATES PATENT OFFICE.

HENRY K. WOLFE, OF CHENEY, WASHINGTON, ASSIGNOR TO ROTARY ROD WEEDEER & MFG. CO., INCORPORATED, OF CHENEY, WASHINGTON.

ROTARY-ROD WEEDEER.

Application filed January 17, 1922. Serial No. 529,965.

To all whom it may concern:

Be it known that I, HENRY K. WOLFE, a citizen of the United States, at present residing at Cheney, in the county of Spokane and State of Washington, have invented certain new and useful Improvements in Rotary-Rod Weeders, of which the following is a specification.

This invention relates to that class of weeders employing rotary rods, an example of which will be found in U. S. Letters Patent No. 981,512 to G. C. and H. K. Wolfe dated January 10, 1911, and U. S. Letters Patent No. 1,338,200 to L. C. Van Patten dated April 27, 1920.

The present invention has for its principal object to provide a rotary rod weeder wherein the rotary rod and its propelling or operating mechanism are all designed as a unit which can be attached to or removed from the vehicle, as a unit, thereby eliminating the necessity of using drive chain tighteners or universal joints, etc., such as are employed in the weeders above referred to; another object is to mount the ground wheel and all of the driving connections between it and the rotary rod in a single standard which is constructed to constitute a boot that encloses and protects the power transmitting mechanism and forms a container, if desired, for lubricant; again it is an object of the invention to provide a simple and inexpensive weeder wherein provision is made to enable the rod to be automatically depressed into the ground or raised therefrom (when draft is applied to the vehicle to move it forwardly) accordingly as the attendant places his weight to the rear or to the front of the vehicle, thereby greatly facilitating the operation of the apparatus.

The invention also resides in those novel features of construction, combination and arrangement of parts, all of which will be fully described and then be specifically pointed out in the appended claims, reference being had to the accompanying drawings, in which:

Figure 1 is a perspective view of one embodiment of the invention.

Figure 2 is a vertical longitudinal section of a portion thereof, on a small scale, illustrating the position of the parts when the rod is beneath the surface of the ground.

Figure 3 is a view similar to Figure 2,

illustrating the position of the parts when the rod has been elevated from the ground, the arrow 22 in Figures 2 and 3 indicating the place of application of the attendant's weight to effect the positioning of the parts as indicated.

Figure 4 is a detail section taken vertically through the boot-standard and showing one form of power transmitting connections.

Figures 5 and 6 are detail views, on a small scale, of a modification of the structure shown in Figure 4.

Figure 7 is a detail view of a modification of the invention, the parts being in the position in which the rotary rod is operative, the arrow 22 indicating the place of the application of the attendant's weight to effect the positioning of the parts as indicated.

Figure 8 is another view of the parts shown in Figure 7 showing the position of the parts when the rod is out of the ground, the place of the attendant's weight being indicated by the arrow 22.

Figures 9 and 10 are detail views of another modification.

Figures 11 and 12 are detail views of still a further modification.

In the drawings in which like numerals of reference designate like parts in all of the figures, the vehicle is composed of side beams or bars 1 connected by cross bars 3 and suitable braces 8, the cross bars 3 being connected by a plank 4 which extends from the front to the rear of the vehicle. At the front, the bars 1 are provided with downwardly extended skids or runners 2 which are adapted to drag along the ground (see Figure 2).

The vehicle is moved forward in the usual way by horse or tractor power connected to the pull 7 which is, in turn, connected to the hitch bar 6 that is linked at 5 to the vehicle.

The rotary rod 17 and the power applying and transmitting mechanism therefor, in the present invention, constitutes a unit which comprises standards 9 and 11, the standard 9 may be of the ordinary flat bar construction and is provided at its lower end with a suitable bearing for the rod 17 and is secured at 10 to the rearwardly projecting portion of one of the bars 1 and braced rigidly at 20 while the standard 11

is likewise rigidly secured at 12 to the opposite bar 1. The standard 11 is so formed as to constitute a boot and it is provided with suitable bearings for the rod 17. The 5 standard 11 is provided with a relatively sharp or narrow front edge 13 from which project, rearwardly, beveled surfaces 14 that aid in penetrating the ground as the vehicle is drawn forward.

10 The ground wheel 15 is mounted on a stub shaft 16 that is journaled in suitable bearings in the standard 11. Power is transmitted from the shaft 16 to the rotary rod 17 through a train of gears 18 mounted on the 15 shaft 16 and rod 17 and on intermediate stub shafts 19. This is the preferred form of power transmission but instead of using a train of gears such as shown in Figure 4, the shaft 16 may transmit its power to the rod 20 17 through beveled gears 23 and a counter-shaft 24, as shown in Figure 5, or the shaft 16 and rod 17 may be provided with sprockets 25 connected by a driving chain 26, as shown in Figure 6.

25 In the operation and use of the invention when draft is applied to move the vehicle forwardly and the operator stands to the rear of the rod 17, on the platform 4, as for instance indicated by the arrow 22 in Figure 2, the rod 17 will automatically enter the ground and by moving backwardly or forwardly while remaining to the rear of the rod 17, the operator can control the distance of penetration of the rod 17 through the 30 mere shifting of his weight on the plank 4 on which he stands, of course, to drive the horses when the vehicle is being pulled by horse power.

By moving forwardly to the position indicated for instance by the arrow 22 in Figure 3, the weight tending to cause penetration of the rod 17 is relieved and the forward pull on the vehicle causes the rod 17 to be lifted out of the ground, as indicated in 45 Figure 3, in which position the vehicle may be transported in an inoperative condition.

In case of injury to the rotary rod or the transmitting connections from the ground wheel 15, the members 9 and 11 may be unbolted from the beams 1 and removed as a 50 unit for the purposes of repair.

Furthermore by the arrangement shown and described, the correct adjustment of the rod for depth in the ground is greatly facilitated.

The boot 11 may be provided with an opening 21 near its top through which suitable lubricant, oil or grease, may be supplied to the gears.

60 It is to be observed that the point of connection 27 of the straps 5 to the vehicle is such that the line of draft (see arrow 28 Figure 3) will fall above the point of fulcrum 29 of the skid 2 with the ground and 65 to the rear of the place where the weight is

applied (see arrow 22) so that the tendency of the draft pull along line 28 Figure 3 will be to lift the rear of the vehicle, thus aiding in effecting the withdrawal of the rod from the ground.

70 While the foregoing form of the invention is a preferred embodiment nevertheless the arrangement of parts shown in Figure 1 may be modified as indicated in Figures 7 and 8 so that the draft device will be located 75 at the end opposite to that shown in Figure 1 in which event the runner 2 will preferably be curved both front and rear.

Instead of using the sled form of vehicle the wheeled form may be used as indicated 80 in Figures 9 to 12 inclusive and the draft may be applied to either end as indicated in Figures 9 and 10 on the one hand and 11 and 12 on the other hand.

85 While I have shown the adaptation of the rotary rod unit to the vehicle of the sled and wheeled type design for being drawn over the ground by animal power or tractor power, other forms of vehicles can be used, as for instance a vehicle having its own driving power, the essential feature of the invention residing in the rotary rod unit and its propelling mechanism, the same being arranged as a unit so that it may be applied in unit form to or removed from the vehicle 90 whatever the construction of the vehicle, per se, may be.

95 From the foregoing description, taken in connection with the accompanying drawings, it is thought the complete construction, 100 the operation and advantages of this invention will be clear to those skilled in the art to which it appertains.

What I claim is:

1. In rotary rod weeders, a vehicle and a combined rod sustaining and propelling unit rigidly mounted on said vehicle.

2. In rotary rod weeders, a tiltable vehicle, means for applying draft to said vehicle, a combined rod sustaining and propelling unit rigidly mounted on said vehicle and pendent therefrom, said vehicle and said unit being so related that by shifting weight on the vehicle from a position in front of the rod to a position in back of the 110 rod, the rod may be automatically entered into the ground and maintained below the surface thereof.

3. In rotary rod weeders, a vehicle comprising a sled having runners, from which 115 extend elevated members, and a combined rod sustaining and propelling unit mounted on said extending members.

4. In rotary rod weeders, a vehicle and a combined rod sustaining and propelling unit 125 mounted on said vehicle and pendent therefrom, said unit comprising a rod carrying standard having a bearing, said standard being formed to constitute a boot, a ground wheel having a shaft journaled in 130

said boot and power transmitting connections between said shaft and said rod and located within said boot.

5. In rotary rod weeders, a vehicle and a combined rod sustaining and propelling unit mounted on said vehicle and pendent therefrom, said unit comprising a rod carrying standard having a bearing, said standard being formed to constitute a boot, a ground wheel having a shaft journaled in said boot and a gear train in the boot connecting said shaft and rod.

6. In rotary rod weeders, a vehicle comprising side bars and cross bars connecting said side bars and skids depending from the front portions of said side bars, and a plank on the cross bars extending, in the longitudinal direction of the vehicle, from front to back; a combined rod sustaining and propelling unit mounted on said side bars and located to the rear of said skids, whereby a shifting of weight on said plank to the front of said rod will cause the rod to be elevated from the ground as the vehicle is drawn along the ground and whereby a shifting of weight on said plank to the rear of said rod will cause said rod to enter the ground as said vehicle is drawn along; and means by which draft may be applied to said vehicle.

7. In rotary rod weeders, a vehicle, means at the front of said vehicle for sustaining the same on the ground, said vehicle having rearwardly projected elevated members, said sustaining means where it engages the ground being curved, a combined rod sus-

taining and propelling unit mounted on said rearwardly extended elevated portions of the vehicle and pendent therefrom and means on which a weight may be shiftably applied to the vehicle whereby, when said vehicle is drawn along and said weight is located in one position, the rotary rod will be elevated from the ground and, when the weight is located in another position, the rotary rod will be depressed under the surface of the ground, substantially as shown and described.

8. In rotary rod weeders, the combination with a vehicle, of standards pendent from the vehicle, a rotary rod journaled in bearings in said standards, one of said standards constituting a boot, a driving shaft mounted in bearings in said standard and a train of gearing connecting said driving shaft with said rotary rod and located within said boot, and means distinct from the vehicle itself and operative by contact with the ground for turning said driving shaft.

9. In rotary rod weeders, a vehicle, a combined rod sustaining and propelling unit relatively fixedly mounted on said vehicle, means by which said vehicle may be moved over the surface of the ground and means by which the shiftable weight may be placed on said vehicle to cause the rod to be depressed beneath or raised above the surface of the ground as the vehicle is moved over the ground, substantially as shown and described.

HENRY K. WOLFE.
